UNITED STATES PATENT OFFICE.

GEORGE M. McCLOSKEY, OF NEW YORK, N. Y.

CLOSET CONNECTION.

1,106,726.

Specification of Letters Patent. Patented Aug. 11, 1914.

Application filed August 6, 1913. Serial No. 783,358.

To all whom it may concern:

Be it known that I, GEORGE M. McCLOSKEY, a citizen of the United States, and a resident of New York, borough of Brooklyn, 5 county of Kings, and State of New York, have invented certain new and useful Improvements in Closet Connections, of which the following is a full, clear, and exact description.

10 This invention relates more particularly to a connection employed for carrying off the waste from water closets, baths, wash-tubs and the like.

One of the principal objects of the invention is to provide a simple and efficient metal connection with a water closet base whereby the connection may be placed in position and proper adjustment secured between the base of the closet and the connection 20 so that the said base may rest directly upon the tiling or floor, thus overcoming many of the objections incident to devices of this kind as ordinarily constructed.

Another object of the invention is to provide simple and efficient means whereby a proper seal may be readily obtained between the connection and the closet base.

A further object of the invention is to provide a simple and efficient closet connection and means for holding the closet base thereto in such a way that various horizontal as well as vertical adjustments may be secured.

A still further object of the invention is to provide a bend of cast iron or other metal having one end enlarged for connection to the closet base and which is adapted to have the waste of bath, washtub or other connections made direct thereto as well as having means serving as a vent connected to said bend.

With these and other objects in view, the invention will be hereinafter more particularly described with reference to the accompanying drawings, which form a part of this specification, and will then be pointed out in the claims at the end of the description.

In the drawings, Figure 1 is a longitudinal section through the connection showing a part of the closet with means for fastening the base to the connection. Fig. 2 is a transverse section taken on the line II-II of Fig. 1. Fig. 3 is a sectional plan view 50 through the base of the closet, the latter being partly broken away, the section being

taken on the line III-III of Fig. 1. Fig. 4 is an enlarged fragmentary section showing a slightly different form of connection for the closet. Fig. 5 is a fragmentary elevation of a part of one member of the connection shown in Fig. 4. Fig. 6 is a fragmentary perspective view of a part of the detachable flange or base of the adjustable member of the connection shown in Fig. 4; 65 and Fig. 7 is an enlarged fragmentary section showing another slightly different form of adjustable member.

The main member or bend 10 is usually made of cast iron though it may be made of other metal or material and has a horizontally extending part 11 and an enlarged vertical part or head 12. The horizontally extending part 11 is connected to the waste pipe and ordinarily inclines slightly in order that the waste may readily flow therefrom. At the enlarged part 12 of the member 10 are openings 13 located on opposite sides thereof to either one of which the usual vent pipe may be connected, the other opening 13 being closed by a plug or otherwise as desired. At the upper part of the enlarged part or head 12 is an annular flange 14 which may be formed integral with the head 12. An adjustable tubular member 15 extends within the head 12 below the flange 14. This member 15 is substantially cylindrical in form and may taper slightly and at the upper edge thereof is provided with a flange or part 16. A holding member 17 has an inwardly extending flange 18 which is adapted to be held under the flange 16 and said holding member 17 is adapted to fit loosely about the member 15 so that it may be rotated and adjusted horizontally. The member 17 is annular in form and is provided with two open ended slotted lugs 19 cut away underneath the same to receive the heads 20 of bolts 21. The bolts 21 have their stem portions or bodies passing through the slots of the lugs 19 and the said bolts are adapted to pass through openings 22 in the base 23 of the closet. On each bolt is a nut 24 and a washer if preferred, and by means of the bolts and nuts the closet base may be rigidly held to the annular holding member 17, the said base being provided with the usual downwardly extending flange 26 which may extend within the adjustable member 15.

It will be evident that the member 15 may be raised or lowered relatively to the head

12 to properly position the flange 16 or upper part of the member 15 with respect to the upper surface of the floor, the latter being indicated at 27. When the member 15 is adjusted properly, it may be packed to form a seal between the same and the head 12 or the adjustment may be made after the packing and sealing has been wholly or partly attended to. The packing and sealing means may be of any suitable kind. As one effective means, the packing 28 may be made by forcing oakum or the like within the chamber formed between the head 12 and the adjustable member 15 above the flange 14 of said head and above the oakum may be lead which may form a lead joint in the usual way, or instead of the packing described, or any other means may be provided. It will be evident also that by reason of the holding member 17 being rotatably held on the member 15, the said holding member may be adjusted horizontally to position the same to correspond to the position of the openings 22 in the closet base so that the base of the closet may be positioned at any desired angle with respect to the position of the member 10. In setting the closet, plaster or paraffin or any other medium may be employed within the chamber 29 under the base in the usual way. By having the member 15 and the means held to the closet base adjustable, the "roughing" may be done at one time and the setting of the closet at another, and in all cases the base of the closet may be made to rest directly upon the tiling or flooring so that a much neater and better job is accomplished with much less labor than by the means ordinarily employed.

40 The horizontal part of the member 10 may be provided with one or more openings 30 to which may be connected the waste pipes from the bathtub, washtubs and the like, thus utilizing the connection not only as a connection for the closet but also for other purposes.

45 In Fig. 4, the construction is substantially the same as already described except that the head 12 of the main member is made without the annular flange 14 and a detachable flange or part 31 is held to the lower edge of the adjustable member 32 which otherwise corresponds in construction substantially to the adjustable member 15 of Figs. 1 to 3. The holding member 17 is first slipped over the body of the member 32 and the flange or part 31 is then held to the lower end of said member 32 and serves to support the packing or sealing means employed to form a seal between said member 32 and the head 12 of the main member or bend 10. The part 31 is annular in form and substantially L-shaped in cross-section. The horizontally extending flange, Fig. 6, is 65 cut away in part to form a plurality of

notches 33 entering each of which is a cam edge 34 which tapers from one side of the slot to the thickness of the flange. On the adjustable member 32 at the lower edge thereof, Fig. 5, are lugs 35 and 36. The lugs 36 are spaced above the lugs 35 to provide a space between the same, and one lug is located to the side of the other lug and said lugs are arranged in pairs. There are as many pairs of lugs 35 and 36 as there are 75 slots 33 in the detachable flange member 31, there being usually four of such slots. It will be apparent that the flange may be passed beyond the lugs 35 by causing the slots 33 of the member 31 to register therewith and by giving a partial slight rotary movement, the flange may be locked between the lugs as the solid part of the horizontal flange will extend over the solid part of the lugs 35 and the cam action of the parts 34 85 engaging the under part of the lugs 36 will force the said flange into locking engagement with the lugs 35 so as to hold the same thereto but in such a way that by reversing the operation described, the said flange may 90 be detached. The flange 31 thus takes the place of the flange 14 of Figs. 1 and 2 and serves to support the packing, as oakum 37, when forced between the adjustable member 32 and the inner surface of the head 12. 95 The oakum serves to form a seal and above the oakum may be provided a lead joint 38 which may be supported by the oakum in the usual way. The holding member may be secured to the closet base as already described, and it will be evident that by the separable adjustable member 32 and the holding member both vertical and horizontal adjustments may be secured.

Fig. 7 shows a construction substantially 105 the same as in Figs. 1 to 3, and differs therefrom mainly in that there is a seal formed between a pendent flange of the closet base and the adjustable member. The main member 10 and the adjustable member as 110 well as the holding member are constructed and held to each other and to the base as in Figs. 1 and 2. The adjustable member 39 of Fig. 7 has an internal flange 40 and on this flange is adapted to rest an L-shaped 115 annular member 41. This member may be of metal though ordinarily I construct the same of pasteboard or paper. The vertical flange 42 of the member 41 may be of thin paper while the base or horizontal part of the member 42 may be of pasteboard. The member 41 has its base 42 resting normally on the flange 40 of the adjustable member and serves as a mold to hold paraffin 43 or other sealing material. The closet base 120 has a pendent flange 44 which is adapted to enter the chamber formed by the annular member 41 and be inserted or embedded in the paraffin 43, or other sealing medium, thus forming a seal at this point. The base 125 130

in this form may have a plaster or other filling about the holding member for setting the base. When the closet is flushed, the water will soften the flange 42 of the member 41 and being of paper will be carried away, but the seal made by the paraffin will remain.

From the foregoing, it will be seen that a simple and efficient connection for water closets is provided; that said connection is so constructed that it serves as a waste or vent for the closet and as a connection for the waste of bath, washtubs or the like; that the connection is so constructed that the 15 "roughing" may be accomplished at any time and the closet set properly without difficulty later on; that the construction is such that skilled mechanics are not necessary to set the closet; that both vertical and horizontal adjustments may be secured; and that a very neat connection is provided so that the closet base may at all times be made to rest upon the tiling or flooring.

Having thus described my invention, I 25 claim as new and desire to secure by Letters Patent:—

1. The combination with a metal bend, of a tubular member adjustable axially with

respect to said bend without turning and having an outwardly projecting flange, sealing means between the bend and adjustable member, the upper surface of said sealing means being flush with the upper surface of said floor, and an annular holding member engaging the upper surface of said sealing means and having an inwardly extending flange engaging below the flange on the adjustable member, and means for securing said holding member to a closet base.

2. The combination with a metal bend to fit in an opening in a floor, of a tubular member adjustable axially within the bend, an annular holding member rotatably connected to the tubular member, a closet having a base to rest upon the floor, means for securing the holding member to the base of the closet, and sealing means arranged below and in contact with the holding member and between the tubular member and end of the bend.

This specification signed and witnessed this 5th day of August A. D. 1913.

GEORGE M. McCLOSKEY.
